(57) **CLAIM**

The ornamental design for a trolley cart, as shown and described.

DESCRIPTION

FIG. 1 is a front elevational view of a trolley cart showing the first embodiment of my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is another perspective view thereof;

FIG. 9 is a front elevational view of a trolley cart showing the second embodiment of my new design;

FIG. 10 is a rear elevational view thereof;

FIG. 11 is a left side view thereof;

FIG. 12 is a right side view thereof;

FIG. 13 is a top plan view thereof;

FIG. 14 is a bottom plan view thereof;

FIG. 15 is a perspective view thereof;

FIG. 16 is another perspective view thereof;

FIG. 17 is an enlarged view of portion 17 shown in FIG. 8;

FIG. 18 is an enlarged view of portion 18 shown in FIG. 8;

FIG. 19 is an enlarged view of portion 19 shown in FIG. 8;

FIG. 20 is an enlarged view of portion 20 shown in FIG. 16;

FIG. 21 is an enlarged view of portion 21 shown in FIG. 16;

and,

FIG. 22 is an enlarged view of portion 22 shown in FIG. 16.

1 Claim, 22 Drawing Sheets
